DESIGN FOR A BOTTLE OR SIMILAR ARTICLE

Sarah C. Calhoun, Frink, Fla.

Application April 24, 1940, Serial No. 91,924

Term of patent 7 years

To all whom it may concern:

Be it known that I, Sarah C. Calhoun, a citizen of the United States, and a resident of Frink, in the county of Calhoun and State of Florida, have invented a new, original, and ornamental Design for a Bottle or Similar Article, of which the following is a specification, reference being had to the accompanying drawing, forming part thereof.

I claim:

The ornamental design for a bottle or similar article, as shown.

SARAH C. CALHOUN.
